UNITED STATES PATENT OFFICE.

JUSTUS P. SEEBURG, OF CHICAGO, ILLINOIS.

DESIGN FOR AN ORGAN CABINET.

Application filed August 1, 1928. Serial No. 27,654. Term of patent 7 years

To all whom it may concern:

Be it known that I, JUSTUS P. SEEBURG, a citizen of the United States, residing at Chicago, in the county of Cook, State of Illinois, have invented a new and original Design for Organ Cabinets, of which the following is a specification, reference being had to the accompanying drawing, forming a part thereof, in which the drawing illustrates a perspective view of the organ cabinet, showing my new design.

I claim:

The new, original, and ornamental design for an organ cabinet as shown.

JUSTUS P. SEEBURG.
